(57) CLAIM

We claim the ornamental design for a plush toy for soothing an infant, as shown and described.

DESCRIPTION

FIG. 1 is a perspective view of a plush toy for soothing an infant showing our new design;

FIG. 2 is a right side elevational view thereof, the left side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a left side elevational view showing the plush toy for soothing and infant in use in a kneeling position, all other views showing the plush toy for soothing an infant in a standing position; the broken lines depict environmental structure for illustrative purposes only and form no part of the claimed design.
